UNITED STATES PATENT OFFICE.

GASTON HERVIEU AND PIERRE MARIE GEORGES MARÉCHAL, OF LONDON, ENGLAND.

SHED FOR AIRSHIPS, AEROPLANES, AND THE LIKE.

1,353,956.

Specification of Letters Patent. Patented Sept. 28, 1920.

Application filed June 19, 1918. Serial No. 240,868.

To all whom it may concern:

Be it known that we, GASTON HERVIEU and PIERRE MARIE GEORGES MARÉCHAL, citizens of the French République, residing at 5 London, England, have invented certain new and useful Improvements in Sheds for Airships, Aeroplanes, and the like, of which the following is a specification.

This invention relates to sheds for airships, aeroplanes and the like, and refers to an improved construction of building of the class in question, which enables the shed or the like to be erected or put together with great facility, the structure moreover being 15 extremely light and yet far stronger than the ordinary shed as at present constructed. A primary object of the invention is to construct the principal units or members of the framework, in such a way that they are extremely strong, are easily adapted to be placed in position upon the ground, can 20 easily be transported from place to place and rapidly put together when the shed has to be erected. Another object of the invention is to provide bridges or their equivalents at the eaves and beneath the ridge, which bridges facilitate the placing in position of the canvas for the walls and roof and enable access to 25 be obtained to a balloon or the like in the shed.

Another object of the invention is to provide, preferably in connection with the bridges located beneath the eaves, lacing 30 boards for facilitating the attachment of the canvas for the walls and roof.

Another object of the invention is to construct the canvas covering constituting the roof in such a way that flaps are formed at 35 the edges which are attached in a special manner in order to prevent the entry of wet and to enable the structure to withstand wind pressure.

Other minor objects of the invention will 40 be pointed out in the description, with reference to the accompanying drawing.

In order that the said invention may be clearly understood it will now be described with reference to the said drawings, in 45 which—

Figure 1 is a front elevation of the framework of the shed, in position, intended more particularly to illustrate the construction of one of the principal units.

Fig. 1^a is a plan of a section of the roof,

and Fig. 1^b is a side elevation of portion of the framework of the shed.

Fig. 2 is a detail view on an enlarged scale showing the method of securing the roof portion to the top of the stanchions, and 60 illustrating also one of the bridges and the board for lacing the canvas covering to the structure.

Fig. 3 is a side view showing the method of lacing the canvas covering to the roof 65 and sides.

Fig. 3^a is a detail view showing a rear portion of the lacing board seen from the inside of the shed.

Fig. 3^b is a sectional plan on the line 3—3 70 of Fig. 2.

Figs. 4 and 5 show sections of the members used for the construction of the principal units of the framework.

Fig. 6 shows complete shed erected with 75 the covering in position.

The same letters of reference are employed to denote the same parts in all the views.

In the present instance each of the principal constructional units comprises two 80 triangular stanchions or trusses connected at their upper end by arched portions to be hereinafter described. Each of the triangular stanchions consists of vertical members 85 a¹, buttress members a², horizontal struts a³ and diagonal struts a⁴.

These stanchions are preferably formed from constructional members illustrated in section at Figs. 4 and 5, in which the table b 90 of the member is composed of wood having a groove c into which the web portion d is inserted and in which it is glued, the whole being made secure by means of screws e or in some cases, the element may be made of 95 double T section comprising two webs d each glued into a corresponding groove and fixed in position by means of screws e.

Each of the stanchions or trusses is provided with a lower horizontal member or 100 sill f, adapted to rest upon the ground.

The portion of the principal unit connecting the side stanchions comprises a laminated arch g, the parts of which are bolted together. It may be constructed with 105 the use of a templet to give the required form. The laminated portion of the arch is supported by means of struts h and in the neighborhood of the eaves by laminated struts h' which are in turn connected to 110

rafters *k* extending from the tops of the stanchions at the eaves to the ridge *m*, as will be seen clearly in the drawing.

Any suitable fish plates, corner plates, brackets or the like may be provided at the joints in the ordinary way for holding the parts together. The lower ends of the arch member and the adjacent vertical members *k'* are supported by brackets 11 carried by 5 and located some distance from the top of the vertical members *a'* of the triangular stanchions, while the outer ends of the rafter *k* are secured to the top of the stanchions by plates 11^c.

15 In erecting the structure any suitable number of these principal units are provided and they are raised into a vertical position at suitable distances apart. They are connected together by longitudinally extending stretchers located at the ridge *m* at the slope of the roof *pp'* at the eaves *q* and up the sides of the stanchions at *r*. The constructional units at the end of the structure are placed somewhat closer together, as 20 shown at the right of Fig. 1^b and these units are connected together by stretchers *r'* arranged at short intervals apart, so as to form a ladder to permit easy access to the bridges at the eaves and at the ridge. The 25 various units may be further strengthened by the provision of diagonal struts *r²*, and diagonally arranged ropes or cables *r³*, as shown in Fig. 1^b.

Underneath the ridge *m* at the bottom of 30 the "king post" *s* is a bridge *t* formed by two vertically disposed planks or beams, only the tops of which are seen in Fig. 1, by means of which access may be obtained to the top of the airship or the like housed in 35 the shed. This bridge also facilitates the process of erection of the shed. Other bridges *w* are also provided, one on each side coming underneath the eaves for facilitating the erection of the shed and for obtaining access to the sides of the airship or 40 the like.

These bridges are formed in sections adapted to fit between the principal units, as shown in Fig. 3^b, and have rigidly connected to them the lacing boards about to be 45 described.

The method of attaching the canvas covering will be understood from the enlarged detail shown at Fig. 2, in which *w* shows the 50 eaves bridge which has attached thereto the lacing board *x* at a suitable angle. The sections of the bridge are placed in position and bolted to the main framework and stretchers.

55 The method of attaching the canvas covering to the structure will be readily understood from the enlarged detail views of Figs. 3 and 3^a in which *w* shows the bridge extending longitudinally beneath the eaves and *x* the lacing board attached thereto. To

the inner side of the lacing board is secured a rod or rods 2 by means of eye bolts or the like. The canvas covering 10 for the walls of the structure is provided with a series of eyes (Fig. 3) at its upper edge through 70 which the rope or cord 10^a is laced, the rope passing through the eyes from the inside of the covering over the upper edge of the lacing board *x* and downwardly underneath the rod 2 after which it is again passed over the 75 upper edge of the board through the next eye of the covering and so on. The covering is attached in a similar manner to the bottom of the side walls by means of a lacing board 3 (Fig. 6), as will be readily understood, but in this case the rod 2 may, if necessary be dispensed with and the board perforated to receive the rope or cord as shown in Fig. 6.

80 The canvas covering 11^a of the roof portion, which is entirely separate from the covering of the walls of the structure has attached to its edges a flap or extension 11^b having a series of eyes formed thereon by means of which said covering is secured to 85 the inner side of the lacing board *x* to the longitudinal rods 2. In this case the ropes 12 are successively passed through the eyes of the flap 11^b under the rod 2 and up through the next adjacent eye as will be 90 clearly seen in Fig. 3^a. The edges of the canvas roof covering 11^a are arranged to overlap the top edge of the canvas covering 10 of the sides as shown in Figs. 2 and 3, and these edges are also provided with eyes 100 or the like for the ropes 4^a, 4^b, secured thereto in the manner known as "crow feet" in connection with the rigging of balloons, the ropes 4^a being attached to the lacing board 3 at the base of the sides. 105

The lacing boards enable the slack of the canvas to be taken up when the canvas is stretched while the method of lacing enables a perfectly tight joint to be obtained preventing the entry of wind or rain to the 110 interior of the shed.

When the structure is erected, bags containing ballast or other suitable weighting means may be provided, placed in the sills *f* in order to give the structure the desired 115 stability.

Any necessary guy ropes such as those indicated at 6, Fig. 6, are provided suitably anchored to the ground.

The ends of the shed are closed by means 120 of canvas curtains arranged so as to form the shape of the prow of a vessel. These curtains are attached to the inner edge of the end principal unit, by means of a lacing board as previously described, and the curtains are provided with any desired number of rows of ropes forming guys properly anchored to the ground. The general arrangement will be seen clearly at Fig. 6.

125 It will be understood that the minor de 130

tails of constructions may be varied without departing from the principle of the invention.

What we claim and desire to secure by 5 Letters Patent of the United States of America is:—

1. In a shed for airships, aeroplanes, and the like comprising in combination a series of principal constructional units consisting 10 of a roof portion supported by triangular stanchions at each side, stretchers between said units located at suitable intervals apart, at the central ridge along the rafters, at the eaves and up the stanchions, bridges between 15 said units located at the eaves and beneath the central ridge, covering means for said structure, boards secured to the bridges located at the eaves, and means on said boards for supporting the covering means.
- 20 2. In a shed for airships, aeroplanes, and the like comprising in combination a series of principal constructional units consisting of a roof portion supported by triangular stanchions at each side; stretchers between 25 said units located at suitable intervals apart at the central ridge, along the rafters at the eaves and up the stanchions, bridges between said units located at the eaves and beneath said central ridge, covering means for said 30 structure, boards secured to the bridges located at the eaves, longitudinal rods secured to the inner faces of said boards by eyes, and means for lacing said covering means to said rods.
- 35 3. In a shed for airships, aeroplanes, and the like comprising in combination a series of principal constructional units consisting of a roof portion supported by triangular stanchions at each side, stretchers between 40 said units located at suitable intervals apart at the central ridge along the rafters, at the eaves and up the stanchions, bridges between 45 said units located at the eaves and beneath the central ridge, lacing boards fixed to the bridges located at the eaves between said units, other lacing boards at the bases of the stanchions, rods secured to the inner faces of said first named boards, canvas covering for said roof, a flap secured to the 50 edges of said covering and adapted to extend to the inner face of said first named lac-

ing boards, means for securing said flap to the rods secured to the inner faces of the lacing boards, and means for securing the edges of said covering to the lacing board 55 secured to the stanchions at their base.

4. In a shed for airships, aeroplanes, and the like comprising in combination a series of principal constructional units consisting of a roof portion supported by triangular 60 stanchions at each side; stretchers between said units located at suitable intervals apart at the central ridge along the rafters at the eaves and up the stanchions, bridges between 65 said units located at the eaves and beneath the central ridge, lacing boards fixed to the bridges located at the eaves between said units, lacing boards located at the base of the stanchions, rods secured to the inner faces of said first named lacing boards, canvas 70 covering for said roof, means for securing the outer edges of said covering to the lacing boards located at the base of the stanchions, a flap secured to the inner edges of said covering and extending to the inner 75 sides of the lacing boards secured to the bridges at the eaves, rods secured to the inner face of said boards, means for securing said flap to the rods, canvas covering for the sides of the structure and means for supporting the upper edges of said side covering adjacent said first named lacing boards by ropes passing over the upper edges of the said lacing boards and under the rods secured to the inner faces thereof. 80

5. In a shed for airships, aeroplanes, and the like, a framework for the walls and roof, a covering for the walls and a covering for the roof, the latter covering being provided with a flap around the edge so that the covering at the top of the wall can be inserted between the edge of the covering for the roof and such flap, and means for holding the edge of the covering and the flap in position on each side of the top of the covering 95 for the wall, for the purposes set forth.

GASTON HERVIEU.
